HAIR CURLER

Paul Tresenberg, Springfield Gardens, N. Y.

Application November 10, 1937, Serial No. 173,879

19 Claims. (Cl. 132—33)

My invention relates to a new and improved hair curling device and to a new and improved method of curling the hair and provides a means to utilize bobbed hair pins and to therein maintain already rolled hair in curled condition on the head.

One of the objects of my invention is to provide an improved device and method for curling a lock of hair and for automatically applying a close legged bobbed hair pin or the like, inserted in the device, to the lock of hair curled on the device so that said pin engages said curled hair when the device is separated from the pin.

Another object of my invention is to provide an improved hair curling device, comprising a novel combination of a bobbed hair pin or the like and a holder therefor; said device having means for clamping the end of a lock of hair and for winding the lock of hair therearound and which means readily permits the disengagement of the wound hair from the device automatically grasped by and retained within the legs of a suitable hair pin.

These and other objects will be readily understood from the following description and accompanying drawing, in which:

Fig. 1 is a side elevation showing the improved device having the hair pin inserted therein and with the spring actuated hair clamping arm open to receive and clamp the free end of the lock of hair to be thence wound on the device.

Fig. 2 is an enlarged longitudinal sectional view of the device showing the parts in normal position.

Fig. 3 is a longitudinal sectional view of the device showing the inner tube in forward position and the hair pin in sprung and released abnormal position.

Fig. 4 is a cross sectional view taken on line 4—4 of Fig. 2.

Fig. 5 is a cross sectional view taken on line 5—5 of Fig. 2.

Fig. 6 is a side elevation showing the inner tube back in normal position with one leg of the hair pin now outside of the curl of hair on the device.

Fig. 7 is a longitudinal sectional view of an embodiment of the device in normal position showing spring mechanism to actuate the inner tube.

Fig. 8 is a longitudinal fragmentary sectional view of the device of Fig. 7, showing the inner tube in forward position and the hair pin leg in released position.

Fig. 9 is a fragmentary section view of an embodiment showing a contracting spring normally holding the inner tube in forward position.

The two cooperating members 10 and 11 are pivoted together at 12. Member 10 is of tapering tubular form having ears 103 and extension 104. A spring 14, is anchored at its one end 141, by a shoulder or the like 115, of finger rest 111, by abutting thereagainst. Its other end 142 lies between said extension 104 and a cap, or the like 15, and thus tends to normally hold members 10 and 11 in closed position as shown in Fig. 2.

Member 11 is preferably constructed as shown but may be tubular or have other suitable form and it has integral ears 113 therewith. At its rear or right extremity it has an integral finger rest 111 which if depressed rocks member 11, about the pivot 12. Said pivot 12 operatively connects members 10 and 11, it being inserted through holes 1031 and 1131 provided in said ears therefor.

The inner cylindrical tube 18 is adapted to move longitudinally within the outer tapered tube 10. Said tube 18 has a shoulder 182 at its rear end and preferably a closed and forward end 186 tapering outwardly. Said end 186 has a lower aperture 185 and an upper aperture 183 which latter is contiguous with a slot 184 provided in the upper wall of tube 18 as shown in Fig. 2. Said slot provides for entry of one leg 171 of a close legged spring metal hair pin 17 (such as the well known bob-pin), which leg 171 and leg 172 inherently normally tend toward each other.

The aperture 185 provides for entry of pin leg 172 therethru as shown in Fig. 2. The said end part 186 may be integral with the tube 18 or may be formed as a separate piece and then fastened to 18 in any well known manner. The shortest distance between said apertures is desirably greater than the distance between the legs at the curved end 173 of the pin so that when the pin is inserted in the device the legs are forced apart and away from each other.

There is also provided preferably integral with the tube 18 a suitable stop 187 adapted to abut against shoulder 157 of the handle 15 to limit the rearward movement of tube 18 relative to member 10. The shoulder 182 of tube 18 abuts against the end 152 of cap 15 to limit the forward movement of tube 18. The device is preferably constructed to free the leg 171 from engagement with the inner surface of member 10 when the tube 18 is in substantially full forward position.

In the embodiment shown in Figs. 7 and 8, a spring 20 having one end 202 preferably fastened to a disc 203 and its other end 201 preferably abutting against the knob 189, preferably ten-

sions the disc against a tongue 109 depressed from member 18 and slidable in slot 188 of tube 18 so as to maintain the tube 18 in rear or normal position. Said tongue 109 and cooperating slot 188 may be provided in the embodiment of Figs. 1 to 6 to maintain the tubes relatively non-rotatable respectively. In another embodiment (Fig. 9) the spring may be arranged to normally position the inner tube in rear position instead of its heretofore described forward position. The forward end of the spring, instead of being attached to the disc 203, is in this embodiment, attached to the tongue 109, to thus maintain the inner tube in forward position. That is, the normally contracting spring now pulls 109 rearwardly, whereas in the prior embodiments, it normally expanded and pushed 109 forwardly. In such case the end 186 may be open, instead of closed and tapered, to permit a pin to longitudinally straddle the end of the inner tube. Forcing said tube and its so mounted pin, rearwardly, causes a pin leg to attain a position over and outside a loop of hair to facilitate grasping the loop within the legs for separation from the device.

In the embodiments of Figs. 7 and 8, after the tube 18 has been pushed forwardly against said spring force to release leg 171 said tube tends to automatically return to rear and normal position as shown in Fig. 7, as is clear to one skilled in the art, and bring with it the pin 17 so the leg 171 assumes its forced open position as shown. The leg is outside of said loop of hair and in relative position to grasp the loop cooperatively with the leg 172 when the pin is separated from the device.

In using the device the hair pin 17 is assembled with the holder as shown in Fig. 2, and preferably before the hair is wound on the device, the resilient legs of the pin now being sprung apart by the heretofore described action of end 186. The end of the lock of hair is clamped between the arm 11 and the tube 10. The operator then may with one hand merely rotate the device including in unison its pin 17, about the longitudinal axis of the device. After the lock of hair has been spirally wound about the device the operator pushes tube 18 forwardly until stop 182 engages cap 152. The leg 171 has now been released from the slot 184 as shown in Fig. 3. The operator then draws tube 18 to its normal and rear position as shown in Fig. 6, the resilient leg 171 now being outside the loop of hair. The pin and its loop of hair are then grasped with the fingers of one of the operator's hands and the device is longitudinally withdrawn therefrom with the other hand. The normal spring action of the resilient pin legs in moving toward each other thus automatically engage the loop of hair when the pin is released from the device.

As many apparently different embodiments of the invention could be devised without departing from the scope thereof it is intended that the foregoing be illustrative and not limiting, and that parts may be used without others.

I claim:

1. In a hair curler, the combination of a close legged hair pin, a tubular member for holding said pin within itself, said member being longitudinally slotted to permit the passage of a leg of said hair pin through the length of the slot, means adjacent said slot for wedging apart the legs of said hair pin, and an outer tubular member, the tubular member being longitudinally slideable within said outer tubular member.

2. In a hair curler, the combination of a close legged hair pin, a tubular member for holding

said pin within itself, said member being longitudinally slotted to permit the passage of a leg of said hair pin through the length of the slot, means adjacent said slot for wedging apart the legs of said hair pin, an outer tubular member, the tubular member being longitudinally slideable within said outer tubular member, and a finger transversely pivoted with reference to the tubular member.

3. In a hair curler, the combination of a close legged hair pin, a tubular member for holding said pin within itself, said member being longitudinally slotted to permit the passage of a leg of said hair pin through the length of the slot, means adjacent said slot for wedging apart the legs of said hair pin, an outer tubular member, the tubular member being longitudinally slideable within said outer tubular member, a finger transversely pivoted with reference to the tubular member, and automatic means normally pressing said finger toward said tubular member.

4. In a hair curler, the combination of a close legged hair pin, a tubular member for holding said pin within itself, said member being longitudinally slotted to permit the passage of a leg of said hair pin through the length of the slot, means adjacent said slot for wedging apart the legs of said hair pin, an outer tubular member, the tubular member being longitudinally slideable within said outer tubular member, a finger transversely pivoted with reference to the tubular member, and automatic means normally pressing said finger toward said tubular member and means to brace said finger away from said tubular member.

5. In a hair curler, the combination of a close legged hair pin, a tubular member for holding said pin within itself, said member being longitudinally slotted to permit the passage of a leg of said hair pin through the length of the slot, means adjacent said slot for wedging apart the legs of said hair pin, an outer tubular member, said tubular member being longitudinally slideable within the outer tubular member.

6. In a hair curler, the combination of a close legged hair pin, a tubular member longitudinally slotted to permit the passage of a leg of said hair pin through the length of the slot, means adjacent said slot for wedging apart the legs of said hair pin, an outer tubular member, the tubular member being longitudinally slideable within the outer tubular member, and a stop on said tubular member limiting its forward movement.

7. In a hair curler, the combination of a close legged hair pin, a tubular member longitudinally slotted to permit the passage of a leg of said hair pin through the length of the slot, means adjacent said slot for wedging apart the legs of said hair pin, an outer tubular member, the tubular member being longitudinally slideable within the outer tubular member, and stops on said tubular member limiting its forward and its rearward movement.

8. In a hair curler the combination of a close legged hair pin, a tubular member longitudinally slotted to permit the passage of a leg of said hair pin through the length of the slot, means adjacent said slot for wedging apart the legs of said hair pin, an outer tubular member, the tubular member being longitudinally slideable within the outer tubular member, and stops on said tubular member limiting its forward and its rearward movement, and a spring within said tubular member tending to hold the forward end of said member within said outer tubular member.

9. The device of claim 8 except that the spring may hold the rearward end of said inner tube within said outer tubular member.

10. In a hair curler, the combination of inner and outer relatively slidable tubes; the inner tube having means for receiving and spreading therewithin the legs of a relatively closed two-legged hair pin; the outer tube normally limiting the spread of said spread pin legs; the inner tube being arranged for projection and retraction longitudinally through said outer tube so that when the inner tube and its received pin are thus projected, one leg of said hair pin moves to above said inner tube and when the inner tube and pin are thence retracted, said moved leg engages the outer surface of the outer tube.

11. The device of claim 10 having a finger transversely pivoted on and cooperating with the outer tube and both adapted to be brought together into intimate relation with a strand of hair having its ends caught therebetween and the curler adapted to be independently turned to wind the hair therearound to form a removable curl.

12. In a hair curler, the combination of inner and outer relatively slidable tubes; the inner tube having means for receiving and spreading therewithin, the legs of a relatively closed legged hair pin; the outer tube normally limiting the spread of said spread pin-legs; the inner tube being arranged for projection and retraction longitudinally through said outer tube so that when the inner tube and its received pin are thus projected, one leg of said hair pin moves to above said inner tube and when the inner tube and pin are thence retracted, said moved leg engages the outer surface of the outer tube; a finger transversely pivoted on and cooperating with the outer tube and both adapted to be brought together into intimate relation with a strand of hair having its ends caught therebetween and the curler adapted to be independently turned to wind the hair therearound to form a removable curl; and automatic means normally pressing said finger toward said outer tube.

13. The device of claim 12 having means to brace said finger away from said tubular member.

14. In a hair curler, the combination of inner and outer relatively slidable tubes; the inner tube having means for receiving and spreading therewithin, the legs of a relatively closed legged hair pin; the outer tube normally limiting the spread of said spread pin-legs; the inner tube being arranged for projection and retraction longitudinally through said outer tube so that when the inner tube and its received pin are thus projected, one leg of said hair pin moves to above said inner tube and when the inner tube and pin are thence retracted, said moved leg engages the outer surface of the outer tube; a finger

transversely pivoted on and cooperating with the outer tube and both adapted to be brought together into intimate relation with a strand of hair having its ends caught therebetween and the curler adapted to be independently turned to wind the hair therearound to form a removable curl; and a stop on said inner tube limiting its forward projecting movement.

15. The device of claim 14 having a stop on said inner tube limiting its rearward retracting movement.

16. In a hair curler, the combination of inner and outer relatively slidable tubes; the inner tube having means for receiving and spreading therewithin the legs of a relatively closed two-legged hair pin; the outer tube normally limiting the spread of said spread pin legs; the inner tube being arranged for projection and retraction longitudinally through said outer tube so that when the inner tube and its received pin are thus projected, one leg of said hair pin moves to above said inner tube and when the inner tube and pin are thence retracted, said moved leg engages the outer surface of the outer tube; and a spring means within said inner tube tending to hold the forward end of the inner tube within said outer tube.

17. The device of claim 16 except that the spring may hold the rearward end of said inner tube within said outer tubular member.

18. In a hair curler, the combination of inner and outer relatively slidable tubes, a finger transversely pivoted on and cooperating with the outer tube and both cooperatively adapted to be brought together into intimate relation with a strand of hair having its ends caught therebetween and the curler adapted to be independently turned to wind the hair therearound to form a removable curl; a longitudinal slot in the wall of said inner tube; the inner tube also having means for receiving and spreading therewithin, the legs of a relatively closed legged hair pin; one pin leg adapted to pass through said slot and outside said inner tube, when said tube is slid forward, and to then engage the loop of wound hair when the tube is retracted; and stops on said inner tube limiting its forward and rearward movement.

19. In a hair curler the combination of, a close-legged hair pin, a tubular member longitudinally slotted to permit the passage of a leg of said hair pin through the length of the slot, means adjacent said slot for wedging apart the leg of said hair pin, an outer tubular member, the tubular member being longitudinally slidably within the outer tubular member, stops on said tubular member limiting its forward and rearward movement, a spring within said tubular member to longitudinally actuate the tubular member in one direction.

PAUL TRESENBERG.
